ABSTRACT: A device for uniformly winding a wire upon a bobbin has a frame structure mounting a wire guide for uniformly distributing the wire upon the bobbin. The frame structure is reciprocated through a distance of predetermined length. It is formed of two parallel bars which are secured against lengthwise displacement relative to each other and alternately frictionally engaged by a cam rotatable about a stationary axis. These engagements cause reciprocating displacement of the frame structure and thus of the wire guide through the predetermined distance during each revolution of the cam.

PATENTED DEC 15 1970

CARL ELIS INSULANDER

DEVICE FOR PRODUCING THE RECIPROCATING MOVEMENT OF THE WIRE GUIDE OF A WINDING MACHINE

The invention refers to a device for producing the reciprocating movement of the wire guide of a winding machine, especially of the kind used for winding of electric coils.

When winding an electric coil, for instance a relay coil on a bobbin with end flanges, it is important that the wire guide reverses its movement exactly in the moment the wire reaches the one end flange or the other.

In a known device of the general kind above referred to a worm gear comprising a left-hand screw and a right-hand screw alternately drives the wire guide in the one direction and the other. In another known device the wire guide is controlled by means of a suitably shaped cam disc, which for each turn of the rotation drives the wire guide to and fro. These known devices are relatively complicated and have the disadvantage that it is difficult to make an exact adjustment of the extreme positions of the wire guide.

It is a broad object of the invention to provide a very simple driving device that has the advantage of an easy adjustment of the extreme positions of the wire guide. This is obtained by the wire guide being mechanically connected to a couple of parallel, spaced-apart bars that, at least with respect to longitudinal movement, are rigidly coupled together, a rotatable semicircular cam disc being located in the space between the bars, for rotational movement in a plane substantially through the longitudinal center lines of the bars. The arrangement is such that during one half revolution the cam disc engages one of the bars and during the second half revolution engages the other bar to drive the bars by friction and thereby moving the wire guide to and fro. Each bar has a stop cleat, adjustable in the longitudinal direction of the bar for cooperation with a stop surface on the cam disc, located at the foremost edge as seen in the rotational movement of said cam disc, to reverse the longitudinal movement of the bars in predetermined positions.

The device will be further described by means of an embodiment with reference to the attached drawing in which

FIG. 1 shows a lengthwise, partly sectional, diagrammatic view of a wire guide driving device with the wire guide in one extreme position,

FIG. 2 is a cross-sectional view of the device according to FIG. 1 on an enlarged scale,

FIG. 3 is a fragmentary view of FIG. 1 showing the driving device in an intermediate position, and

FIG. 4 is a fragmentary view similar to FIG. 3 and showing the driving device in the other extreme position.

In FIG. 1 there is shown a wire guide 1 for guiding a wire 2 that, coming from a wire supply spool 3, is wound onto a bobbin 4 when rotated. During the winding of the wire onto the bobbin which has flanges 5 and 6 the wire guide must be axially reciprocated with an even speed between two extreme positions, so that the wire is evenly wound on the bobbin.

For this purpose, the wire guide is fixed to one end of a bar 7 of a driving device. The bar is guided between rollers 7a and mounted in parallel with a second bar 8. The bars are prevented, by means of two crosswise connection pieces 9 and 10, from moving lengthwise relative to each other thereby constituting a frame structure. Bar 8 is biased towards bar 7 by means of springs 17a and 18a biasing bolts 17 and 18. On a rotary shaft 12 located perpendicularly to the plane of the bars is keyed a semicircular cam disc 11, and on either side of the cam disc there are arranged two support wheels 13 and 14, mounted on ball bearings 25 and 26 and defining support paths 15 and 16 for the bars 7 and 8. The radii of the support paths are somewhat smaller than the radius of the cam disc 11 (see FIG. 2) so that during the rotation of the shaft the cam disc during one-half of each turn lifts the one bar from the support paths and during the other half turn lifts the other bar. As shown, the radius of support path 15 is such that there is always a gap 31 between crossbars 9 and 10 and bar 8. Assum-

ing, by way of example, that wire guide 1 is somewhat to the left from the position shown in FIG. 1 and is moving toward the left. During this movement, disc 11 is in pressure engagement with bar 7 but not with bar 8. When the wire guide reaches the position of FIG. 1, the disc is in pressure engagement with both bars for the short time until the reverse movement begins. The two bars are now spread apart and hence, bar 7 together with pieces 9 and 10, is lifted. The lifting distance is a very short one, in practice less than 1 mm. The bar can be lifted through such short distance in spite of the restraint by guide rolls 7a. The bar lifted by the cam disc is lengthwise displaced by the friction between the respective bar and the cam disc as provided by the spring-loaded bolts 17 and 18, in the tangential direction of the disc, the other bar following in the same direction resting upon the support paths. Thus the wire guide obtains the required reciprocating movement.

In order to permit adjustment of the device, so that the wire guide reverses its movement exactly in the positions in which the wire reaches the inner sides of the flanges 5 and 6 of the bobbin, that is, without continued inertia movement, each bar is provided with a stop cleat 19 and 20 respectively, each of which is fastened to the bars, in a manner such that it can be adjusted to a desired position lengthwise of the bar as is indicated by a slot 30 in the bars. The wire guide 6 always reverses its movement when the front edge 21 of the cam disc engages the respective stop cleat 19 or 20.

I claim:

1. A device for uniformly winding a wire upon a bobbin, said device comprising in combination:

a wire guide for uniformly distributing the wire upon a bobbin; and

a driving means for imparting to the wire guide a reciprocating movement of a predetermined stroke length, said driving means including:

a frame structure comprised of two parallel bars spaced apart and secured against lengthwise displacement relative to each other by cross bars permitting limited movement of the parallel bars toward and away from each other, and spring means biasing said parallel bars toward each other, said wire guide being secured to said frame structure; and

a cam means mounted between said parallel bars unidirectionally rotatable about an axis normal to the length of the bars, said cam means having a circumferentially elongate camming surface alternately engaging the parallel bars with frictional pressure engagement during one-half of each revolution of the cam means, each of the intermittent pressure engagements causing lengthwise displacement of the engaged one of the bars in opposite direction by a distance determined by the circumferential length of the camming surface, the respective nonengaged bar automatically following such displacement whereby the frame structure and the winding guide secured thereto are reciprocated by said distance.

2. The device according to claim 1 and comprising a pair of stop means, each lengthwise displaceably mounted on one of said bars, said stop means arresting the lengthwise displacement of the frame structure relative to the rotary cam means at selected positions in either direction.

3. The device according to claim 1 and comprising a rotary shaft transversely extending through the frame structure between the two parallel bars thereof, said cam means being seated on said shaft for said alternate coaction with said bars, and a pair of support wheels mounted on said shaft on opposite sides of the cam means and protruding beyond the edges of the parallel bars for guiding said bars as the frame structure is lengthwise reciprocated relative to the cam means.

4. The device according to claim 1 wherein one of said parallel bars is lengthwise extended beyond the other bar, said extension mounting said wire guide.
